CONTROL APPARATUS

Roswell Harry Herrick, Oak Park, Ill., assignor to
Associated Electric Laboratories, Inc., Chicago,
Ill., a corporation of Delaware

Application March 19, 1938, Serial No. 196,919

12 Claims. (Cl. 179—16)

The present invention relates to control apparatus and more particularly to improvements in impulse responsive relay networks wherein electronic devices are utilized to control electro-
5 magnetic relays comprising impulse repeating apparatus.

In an arrangement of the character mentioned, the input or control voltage is usually impressed on the input electrodes of an electron discharge device having included in its output circuit a control relay or other electromagnetic control device which is traversed by the anode current of the controlling electron discharge device. In time, the anode current flowing through the re-
10 lay winding causes residual magnetism to be developed in the core of the relay. As a consequence, the relay is prevented from properly responding to variations in the voltage impressed on the input electrodes of the controlling elec-
15 tron discharge device. This problem is particu-
20 larly troublesome in networks wherein the control relay and the electron discharge device are arranged to respond to the impulses of an impulse train, such, for example, as impulse trains
25 of the character utilized in controlling automatic switches conventionally used in automatic telephone systems. More particularly, in an impulse responsive network of this character, it is highly desirable to utilize the steep linear portion of the
30 grid voltage-anode current characteristic of the electron discharge device as the operating range within which the grid voltage is varied in response to received impulses. By utilizing this portion of the characteristic curve, it is possible to obtain
35 the maximum change in the anode current traversing the control relay winding for a given change in the input voltage impressed on the input electrode of the electron discharge device. When this portion of the characteristic curve is
40 used, however, the electron discharge device usually is not, even during periods of non-use, biased beyond cutoff and, hence, a steady direct anode current continuously traverses the winding of the control relay. This steady current tends
45 to produce residual magnetism in the core of the relay which renders the relay sluggish in operation or restoration, thereby tending to produce distortion in the repeated impulses.

It is an object of the present invention to pro-
50 vide an exceedingly simple arrangement of the character briefly outlined above wherein the steep linear portion of the grid voltage-anode current characteristic curve of the controlling electron discharge device may be used as the range with-
55 in which the input voltage is varied, and wherein

positive response of the control device to changes in the input voltage impressed on the input electrodes of the electron discharge device is at-
tained.

It is a further object of the invention to pro-
5 vide an improved impulse responsive network of the form described wherein the character of the output or repeated impulses is, within limits, substantially independent of the character of the received impulses.

In the illustrated embodiment of the invention, there is shown a pulsing relay including a wind-
10 ing and a control armature, a condenser, a source of potential for charging the condenser, and a second relay for alternately connecting the con-
15 denser to be charged from the source and to dis-
charge through the winding of the pulsing relay, thereby to cause alternate operation and restora-
20 tion of the control armature. For the purpose of controlling the second relay, there is provided an electron discharge device including an input electrode and output electrodes, with suitable
25 apparatus for impressing pulses of input volt-
age on the input electrode. The second relay, mentioned above, is connected and arranged to be energized in accordance with the current flow-
30 ing in the output circuit of the electron discharge device. In order to render this second relay posi-
35 tive in operation or to obviate the difficulty as mentioned above, there is also provided circuit apparatus for passing a second current through
40 the winding of the second relay in opposition to the anode current of the electron discharge de-
45 vice, and of a magnitude substantially different in one sense than the magnitude of the anode current when impulses of input voltage are im-
50 pressed on the input electrode of the electron dis-
charge device. Further to accomplish this end, additional apparatus is provided for changing the magnitude of the anode current to a value different in the said one sense than the value of the second or opposing current during the intervals when no input voltage is impressed on the input electrode of the electron discharge de-
55 vice. By this arrangement, the direction of cur-
rent flow through the winding of the second re-
lay is reversed at the beginning and end of each pulse of input voltage impressed on the input electrode of the electron discharge device and the effects of residual magnetism are substan-
60 tially obviated.

In order to render the repeated or output impulses of the impulsing relay sub-
stantially independent of the pulses of input volt-
age applied to the input electrode of the electron discharge device, an additional impedance ele-

ment is provided in shunt with the winding of the pulsing relay; and the impedance of the winding of the impulsing relay, the capacitance of the condenser for energizing this winding, and the impedance of the additional impedance element are so proportioned relative to each other that the ratio of the restored intervals to the operated intervals of the pulsing relay is, within limits, independent of the ratio of the corresponding periods for the relay having its winding included in the output circuit of the electron discharge device.

The novel features believed to be characteristic of the invention are set forth with particularity in the appended claims. The invention, both as to its organization and method of operation, together with further objects and advantages thereof, will best be understood by reference to the specification taken in connection with the accompanying drawing, in which Figure 1 illustrates an arrangement having incorporated therein the features of the present invention as outlined above; and Fig. 2 is a graph illustrating the operating characteristic of the arrangement shown in Fig. 1.

Referring now more particularly to Fig. 1 of the drawing, there is shown an impulse responsive network which is arranged to receive impulses of alternating input voltage impressed between the input terminals 10 of a transformer 11 and to repeat these impulses over a circuit including the terminals 12 connected to armature springs controlled by an armature 13 of a pulsing relay 14. The network comprises an electron discharge device 15 in the form of a vacuum tube having an input electrode or control grid 16 and a pair of output electrodes comprising a cathode 17 and an anode 18. The transformer 11 is provided with a secondary winding 19 which is coupled between the input electrode 16 and the cathode 17 by a capacitance element 20. Coupled to the output electrodes of the device 15 is an output circuit which comprises the winding 21 of a control device or relay 22 and the portion 23 of a voltage dividing resistor 24. The resistor portion 24 and the winding 21 are by-passed for alternating currents by a capacitance element 25. In order that the grid voltage of the discharge device 15 may be varied within the optimum or steep linear portion of its grid voltage-anode current characteristic in response to pulses of input voltage during operation of the network, the source of bias voltage comprising the drop across the portion 26 of the resistor 24 is arranged to be impressed by way of circuit connections including the secondary winding 19 of the transformer 11 on the input electrode 16. In order to obviate the difficulty mentioned above or to insure positive response of the relay 22 to variations in input voltage, a priming circuit is provided for passing a current through the winding 21 of this relay in opposition to the anode current normally flowing in the output circuit of the electron discharge device 15. This priming circuit includes a portion 27 of the resistor 24 and a second resistor 28 of relatively high resistance. A source of direct voltage, not shown, is connected between the terminals +B and -B of the voltage dividing resistor 24.

70 The relay 22 is provided with an armature spring 29 which is arranged to be operated between two contacts 30 and 31 to control the energization and deenergization of the pulsing relay 14. More particularly, the armature 29 is connected to one electrode of a condenser 32 which

is arranged to be charged over two conductors 33 and 34 from a source of voltage, not shown, but having its terminals connected to the terminals 35 and 36. A circuit comprising the conductor 34 and a third conductor 37 is provided for discharging the condenser 32 through the winding of the pulsing relay 14. In order further to control the period of energization of the relay 14, an additional impedance element in the form of a condenser 38 is provided which is connected 10 in shunt with the winding of the relay 14.

The operation of the network illustrated in Fig. 1 may best be described by reference to the graph illustrated in Fig. 2. In brief, when the network is conditioned for operation and no alternating current impulses are impressed between the input terminals 10 of the transformer 11, two components of current are flowing through the winding 21 of the relay 22. The first of these components of current is the anode 20 current which flows from the +B terminal of the voltage supply source by way of the anode 18, the electron stream between this anode and the cathode 17, the winding 21 to the negative side of the resistor portion 24. The magnitude 25 of this first component of current is determined by the bias impressed on the input electrode 16 of the electron discharge device 15, and, preferably, this bias is chosen of a value e_b which corresponds to the knee of the grid voltage-anode 30 current curve A, whereby the steep linear portion of the curve lying between a and b may be utilized as the range within which the grid voltage is varied when an impulse of input current is impressed on the input terminals 10. With a bias 35 voltage of e_b , the anode current or the first component of current flowing through the winding 21 is i_a , as indicated in Fig. 2. This first component of current i_a may be termed as being of a positive polarity. The second component of current mentioned above and flowing through the winding 21 is that which flows through the priming circuit including the portion 27 of the resistor 24 and the resistance element 28. By examination of the circuit arrangement of Fig. 1, it will be seen 40 that this second component of current is in opposition to the anode current, since it flows from the positive side of the resistor portion 27 by way of the winding 21 and the resistor 28 to the negative side of the resistor portion 27. 45 Hence, the second component of current may be designated as being of negative polarity. This second component of current, the magnitude of which is indicated in Fig. 2 is at i_p is substantially 50 different in one sense; that is, it is substantially greater than the anode current i_a when no input voltage is impressed between the input terminals 10 of the transformer 11. The net current flowing through the winding 21 is the difference between the two currents i_p and i_a and is indicated 55 in Fig. 2 as being of a magnitude i_n , which is of a negative polarity. The magnitude of the current i_n is maintained at a value less than the value of current required for operation of the relay 22 and, hence, this relay remains restored when no input voltage is impressed between the terminals 10. By suitably proportioning the resistance value of the resistor 28 or by energizing the priming circuit from a source having a proper voltage, the 70 net current i_n may be made to approach a zero value. Thus, if the current i_n is made equal to i_p when no input voltage is impressed on the terminal 10, the net current flowing through the winding 21 is zero. In this connection it is 75

pointed out that the resistance of the priming circuit and, more particularly, the resistor 28, is made high relative to the resistance of the winding 21, so that no substantial portion of the direct component of the anode current flowing in the output circuit of the device 15 is by-passed around the winding 21.

With the relay 22 restored, the condenser 32 is connected by way of the circuit including the two conductors 33 and 34, the contact 30 and the armature 29 across the source of voltage connected between the terminals 35 and 36. Thus, the condenser 32 is charged to the voltage existing between the terminals 35 and 36. When a received pulse of alternating voltage, as indicated at B, is applied to the terminals 10, this voltage is impressed between the input electrode 16 and the cathode 17 through the transformer 11 and the coupling condenser 20. On one-half of each cycle of this voltage, the negative potential on the electrode 16 is reduced to a value e_p so that the anode current is increased to a theoretical maximum value i_m . The average or effective value of the current flowing in the anode circuit of the device 15 during repeated positive half cycles of the input voltage is something less than the maximum and is indicated at i_a . In this connection, it is pointed out that the condenser 25 acts as a smoothing capacitance to reduce the peaks and increase the valleys of the anode current such that it approaches the average value indicated. This average value, as indicated, greatly exceeds the opposing component current i_p flowing through the winding 21 as a consequence of the provision of the priming circuit. The difference between the two components of current is indicated at i_o . This current is of a positive polarity and is above the value required to cause operation of the relay 22. As a consequence, this relay operates to move the armature 29 from engagement with the contact 30 and into engagement with the contact 31 so that the charged condenser 32 discharges through the winding of the relay 14 and the condenser 38 in parallel. This current is sufficient to cause the operation of the relay 14 so that the armature 13 is moved into engagement with its associated contact to repeat the pulse over the circuit connected to the terminals 12. Obviously, when the pulse is ended, so that the alternating input voltage B is no longer applied to the input electrode 16, the anode current is reduced from the average value i_a to the steady state value i_o . When this occurs, the priming current i_p again predominates and the net current flowing through the winding 21 is reduced to the negative value i_n . Hence, the relay 22 is caused to restore to reconnect the condenser 32 to again be charged from the voltage source connected to the terminals 35 and 36. During each succeeding pulse of input voltage impressed on the the electrode 16, the above-described sequence of operations is repeated.

From the foregoing description it will be apparent that, during a series of received impulses, the direction of current flow through the winding 21 of the relay 22 is reversed at the beginning and the end of each pulse of input voltage. Thus, the effect of any residual magnetism which may be developed in the core of the relay 22 is substantially obviated. It will also be noted that, by normally biasing the discharge device 15 to the knee of its grid voltage-anode current characteristic curve, the steep and relatively linear portion of the curve lying between the points a and b 75 is the operating range of the curve through which

the grid voltage is normally varied when the input voltage pulses are impressed on the electrode 16. By biasing the tube to this point, the maximum change in the anode voltage is secured for a given change in the voltage applied to the electrode 16. As indicated in the introductory portion of the specification, the particular arrangement of the circuit for energizing the pulsing relay 14 is such that the ratio of the closed contact period to the open contact period of this relay during each impulse may, within limits, be rendered independent of the ratio of the corresponding periods for the relay 22. More particularly, when the relay 22 is operated to connect the condenser 32 to discharge through the winding of the relay 14, the time interval during which the last-mentioned relay will be sufficiently energized to stay operated depends upon the time constant of the circuit including this winding, the condenser 38 and the charge condenser 32. By suitably proportioning the capacitance of the condenser 32, the capacitance of the condenser 38, and the impedance of the winding of the relay 14 relative to each other, the time constant of the circuit may be rendered such that the relay 14 will restore before the restoration of the relay 22 or, alternatively, will remain operated during the entire interval when the relay 22 is operated. Again, by suitably proportioning the capacitance of the condenser 38 with respect to the impedance of the winding of the relay 14, the demagnetization of this relay at the end of each period of energization may be delayed sufficiently so that the relay 14 will remain operated after the restoration of the relay 22. Thus, by suitably varying the capacitance values of the two condensers 32 and 38, the portion of each impulsive period during which the relay 14 is operated may be varied within wide limits. By this arrangement, the ratio of the open circuit to the closed circuit periods of the circuit connected to the terminals 12 may be adjusted to suit the requirements of any particular application.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. An impulse responsive network comprising, in combination, a first relay including a winding and a control armature, a condenser, a source of potential for charging said condenser, a second relay for alternately connecting said condenser to be charged from said source and to discharge through the winding of said first relay, thereby to cause alternate operation and restoration of said control armature, an electron discharge device including an input electrode and output electrodes, means for impressing pulses of input voltage on said input electrode, an output circuit coupled to said output electrodes, said second relay including a winding connected and arranged to be energized in accordance with the current flowing in said output circuit, means for passing a second current through the winding of said second relay in opposition to said first-mentioned current and of a magnitude substantially different in one sense than the magnitude of said first-mentioned current when said pulses of input voltage are impressed on said input electrode, and means for changing the magnitude of one of said currents so that the magnitude of said 70 currents is substantially obviated. It will also be noted that, by normally biasing the discharge device 15 to the knee of its grid voltage-anode current characteristic curve, the steep and relatively linear portion of the curve lying between the points a and b 75 is the operating range of the curve through which

first-mentioned current is equal to or different in said one sense than the magnitude of said second current during the intervals when no pulses of input voltage are impressed on said input electrode.

2. An impulse responsive network comprising, in combination, a first relay including a winding and a control armature, a condenser, a source of potential for charging said condenser, a second relay for alternately connecting said condenser to be charged from said source and to discharge through the winding of said first relay, thereby to cause alternate operation and restoration of said control armature, an additional impedance element shunting the winding of said first relay; the impedance of the winding of said first relay, the capacitance of said condenser and the impedance of said additional impedance element being so proportioned relative to each other that the ratio of the restored intervals to the operated intervals of said first relay is, within limits, independent of the ratio of the corresponding periods for said second relay during a series of impulses delivered to said second relay; an electron discharge device including an input electrode and output electrodes, means for impressing pulses of input voltage on said input electrode, an output circuit coupled to said output electrodes, said second relay including a winding connected and arranged to be energized in accordance with the current flowing in said output circuit, means for passing a second current through the winding of said second relay in opposition to said first-mentioned current and of a magnitude substantially different in one sense than the magnitude of said first-mentioned current when said pulses of input voltage are impressed on said input electrode, and means for changing the magnitude of one of said currents so that the magnitude of said first-mentioned current is equal to or different in said one sense than the magnitude of said second current during the intervals when no pulses of input voltage are impressed on said input electrode.

3. An impulse responsive network comprising, in combination, a first relay including a winding and a control armature, a condenser, a source of potential for charging said condenser, a second relay for alternately connecting said condenser to be charged from said source and to discharge through the winding of said first relay, thereby to cause alternate operation and restoration of said control armature, an electron discharge device including an input electrode and output electrodes, means for impressing pulses of input voltage on said input electrode, an output circuit coupled to said output electrodes, said second relay including a winding connected to be traversed by the current flowing in said output circuit, means for passing a second current through the winding of said second relay in opposition to said first-mentioned current and of a magnitude substantially different in one sense than the magnitude of said first-mentioned current when said pulses of input voltage are impressed on said input electrode, a source of biasing potential, circuit connections for impressing the voltage of said source on said input electrode, and means including said source and said circuit connections for changing the magnitude of said first-mentioned current to a value different in said one sense than the value of said second current during the intervals when no pulses of input voltage are impressed on said input electrode, whereby the direction of current flow

through the winding of said second relay is reversed at the beginning and end of each pulse of input voltage impressed on said input electrode.

4. An impulse responsive network comprising, in combination, a first relay including a winding and a control armature, a condenser, a source of potential for charging said condenser, a second relay for alternately connecting said condenser to be charged from said source and to discharge through the winding of said first relay, thereby to cause alternate operation and restoration of said control armature, an additional impedance element shunting the winding of said first relay; the impedance of the winding of said first relay, the capacitance of said condenser and the impedance of said additional impedance element being so proportioned relative to each other that the ratio of the restored intervals to the operated intervals of said first relay is, within limits, independent of the ratio of the corresponding period for said second relay during a series of impulses delivered to said second relay; an electron discharge device including an input electrode and output electrodes, means for impressing pulses of input voltage on said input electrode, an output circuit coupled to said output electrodes, said second relay including a winding connected to be traversed by the current flowing in said output circuit, means for passing a second current through the winding of said second relay in opposition to said first-mentioned current and of a magnitude substantially different in one sense than the magnitude of said first-mentioned current when said pulses of input voltage are impressed on said input electrode, a source of biasing potential, circuit connections for impressing the voltage of said source on said input electrode, and means including said source and said circuit connections for changing the magnitude of said first-mentioned current to a value different in said one sense than the value of said second current during the intervals when no pulses of input voltage are impressed on said input electrode, whereby the direction of current flow through the winding of said second relay is reversed at the beginning and end of each pulse of input voltage impressed on said input electrode.

5. Electrical control apparatus comprising, in combination, an electron discharge device including an input electrode and output electrodes, means for impressing an input voltage on said input electrode, an output circuit coupled to said output electrodes, a control device having a winding connected and arranged to be traversed by a current which varies substantially in accordance with the current flowing in said output circuit, means for passing a second current through said winding in opposition to said first-mentioned current and of a magnitude substantially different in one sense than the magnitude of said first-mentioned current when any substantial input voltage is impressed on said input electrode, and means for changing the magnitude of one of said currents so that the magnitude of said first-mentioned current is equal to or different in said one sense than the magnitude of said second current when the input voltage impressed on said input electrode is reduced to a predetermined value.

6. Electrical control apparatus comprising, in combination, an electron discharge device including an input electrode and output electrodes, means for impressing an input voltage on said input electrode, an output circuit coupled to said

than the magnitude of said first-mentioned current when any substantial input voltage is impressed on said input electrode, the resistance of said priming circuit being so proportioned relative to the resistance of said winding that no substantial portion of the direct component of the current in said output circuit is by-passed around said winding and through said priming circuit, and means for changing the magnitude of one of said currents so that the magnitude of said first-mentioned current is different in said one sense than the value of said second current when the input voltage impressed on said input electrode is reduced to a predetermined value, whereby the direction of current flow through said winding is reversed when said input voltage is decreased from said substantial value to said predetermined value and when said input voltage is increased from said predetermined value to said substantial value.

12. Electrical control apparatus comprising, in combination, an electron discharge device including an input electrode and output electrodes, means for impressing an input voltage on said

input electrode, an output circuit coupled to said output electrodes, an electro-magnetic control device including a core, a winding and a control element operative between two positions, said winding being connected and arranged to be traversed by the current flowing in said output circuit, means for passing a second current through said winding in opposition to said first-mentioned current and of a magnitude substantially different in one sense than the magnitude 10 of said first-mentioned current when any substantial input voltage is impressed on said input electrode, and means for changing the magnitude of said first-mentioned current to a value different in said one sense than the value of said second current when the input voltage impressed on said input electrode is reduced to a predetermined value, whereby the direction of current flow through said winding is reversed each time said input voltage is varied between said substantial and said predetermined values and said control element is positively operated between its said two positions.

ROSWELL HARRY HERRICK.
